ELECTROLYTICALLY GENERATED OXYGEN FOR CAUSTIC RECOVERY

Charles W. Rippie, Ashland, Ky., and Howard B. Bishop, Summit, N. J., assignors to H. Berkey Bishop, Morristown, N. J.

Application December 18, 1956, Serial No. 629,191

8 Claims. (Cl. 208—235)

This invention relates to the oxidation of mercaptides to disulfides in aqueous alkaline reacting solutions and to other reactions which require oxidation.

In the refining of petroleum oils to eliminate some of the chemical components which detract from the value of the oil and particularly in the desulfurization of gasoline large quantities of caustic solutions are normally employed.

The usual procedure is to treat the gasoline first to remove hydrogen sulfide, then caustic soda or other alkaline hydroxides are used for the extraction of mercaptans. Several methods have hitherto been employed for the regeneration of the hydroxides including the following:

(1) One method is to add doctor solution which consists of sodium plumbite, which, combined with free sulfur, results in the oxidation of mercaptides and other sulfur-hydrol compounds to innocuous disulfides and the precipitation of the lead as lead sulfide. This procedure involves the regeneration of the spent doctor solution by oxidation for the recovery of lead sulfide.

(2) Another method of regenerating the hydroxides is to utilize the solution containing the aqueous mercaptides as an electrolyte and pump the solution through one or more electrolytic cells where the water is broken down and oxygen produced which combines with the alkaline mercaptides and forms disulfide.

The first process utilizing the doctor solution has the disadvantage of leaving the disulfides in the gasoline and requiring the regeneration of the spent doctor.

The second process, which is generally known as the internal electrolytic regeneration process, has the disadvantage that the caustic solution employed in the treating process must be such as to constitute a favorable electrolyte in the electrolytic cell and therefore the selection of the caustic treating solution is in the nature of a compromise between the conditions desired for treating the gasoline and the conditions necessary to maintain the electrolytic cell. This process has the additional disadvantage that the solution must of necessity move slowly through the cell, and the oxygen produced by the electrolysis of the very solution being treated modifies the solution and provides no means for effectively mixing the oxygen produced with the solution. Also the electrolytic cell is subject to rapid deterioration because corrosive substances are formed inside the cell.

This invention has for its purpose the utilization of an electrolytic cell with an ideal electrolyte for the production of oxygen and the efficient use of the oxygen outside of the cell for the regeneration of the spent caustic. It is thus possible to utilize the most economical and satisfactory caustic solution for the treatment of gasoline without reference to whether or not it would be a satisfactory electrolyte.

It has been found to be entirely feasible to employ a high cost caustic such as caustic potash inside the cell, since it will not wear out for a long period of time, such as five years, and is more desirable and satisfactory as an

2

electrolyte for use in the cell. At the same time it is entirely feasible to employ a low cost caustic, such as caustic soda, for treating the gasoline since it does not enter the cell and is not relied upon as an electrolyte.

5 Other satisfactory electrolytes, such as an acid, may be employed since the oxygen produced in the cell is to be used outside of the cell.

This invention takes advantage of the fact, which we have discovered, that the oxygen generated in the electrolytic cell is a more active oxygenating agent than bottle oxygen, which is generally understood to be molecular oxygen, not only as produced in the cell but also for a substantial length of time after it is drawn off from the cell.

According to this invention we therefore employ the oxygen generated by electrolysis within the cell, outside of the cell by bringing it quickly into reacting contact with the solution containing the mercaptides before its activity has reverted to that of bottle oxygen.

10 This invention has, among other advantages, the following:

(1) A highly efficient and effective electrolytic cell is maintained with a substantially constant electrolyte, such as caustic potash, by merely adding water to replace that which is decomposed in the cell into hydrogen and oxygen without any contamination or change which takes place when oxidation of the mercaptides is going on within the cell, as in the prior art process as described, for example, in Gaylor Patent No. 2,654,706.

15 (2) The oxygen generated in the cell is drawn quickly into contact and reacts with the spent caustic from the treatment of the gasoline which is thereby effectively regenerated outside of the cell. The disulfides are washed out of the regenerated caustic solution by naphtha in the usual way.

20 It has been discovered that the caustic recovered by the use of this invention is so much more effective in treating gasoline than caustic regenerated by other means that the lead susceptibility of the gasoline is very substantially increased.

25 The process of this invention may be readily understood by reference to the attached drawings in which:

Fig. 1 is a flow diagram of a process embodying our invention for treating sour gasoline with caustic and continuously regenerating the caustic with oxygen drawn directly from an electrolytic cell.

30 Fig. 2 is a flow diagram of a process for treating waste waters in accordance with our invention whereby they are rendered suitable for discharge into lakes or rivers without improper contamination; and

35 Fig. 3 is a cross-sectional view of an eductor which is suitable for use in either of the processes illustrated in Figs. 1 and 2.

40 Referring to Fig. 1 sour gasoline to be treated is introduced through line 1 into a packed tower 2 where it is given an initial caustic treatment for removing the hydrogen-sulfide (H_2S) and from which it flows through line 3 to the treating tower 8.

45 The sour gasoline enters tower 2 near the bottom and discharges at the top, a suitable treating fluid, such as caustic soda, is supplied through line 4 and valve 5 into the packed tower 2 near the top and may be drawn out near the bottom through valve 6 and discharge line 7. This operation is operated primarily as a batch operation so far as the caustic wash is concerned, foul caustic being withdrawn periodically, for example, once a week and fresh caustic supplied from line 4 through valve 5. The initially treated gasoline enters packed tower 8 near the bottom and leaves at the top through line 9 from which it passes through a knock-out drum 10 in the usual manner and leaves through line 11 as treated product.

70

A stream of treating fluid, such as caustic soda, is supplied through line 12 and enters tower 8 at its upper end and is withdrawn at the bottom of the tower through line 13 and enters spent caustic tank 14 from which it is picked up by a pump 15 and is forced through valve 16, eductor 17 and valve 18, and recirculates through the pump. This recirculation continues under conditions which are controlled by the valves and results in drawing oxygen directly from the electrolytic cell 21 into the suction side of the eductor from line 19, which is connected through valve 20 to the cell. The eductor 17 shown in detail in Fig. 3 of the drawings is operative by reason of substantial pressure which is exerted by the pump 15, which as above described, forces the caustic solution from tank 14 through the eductor. The eductor requires a high pressure at the nozzle which is suddenly released, as is well known. Moreover, the oxygen which is drawn into the ejector is intimately mixed with the caustic stream by reason of these characteristics of the eductor. The mixing is further augmented by the action of the pump 15 which, as shown, rapidly circulates the mixed solution and oxygen through the circuit comprised of the pipe 24, valve 16, eductor 17 and the valve 18. The electrolytic cell contains an electrolyte which is well adapted to the continuous production of oxygen by electrolysis, such as for example, a caustic potash solution, and the direct current electricity is supplied to the cell by rectifier 22, which may be connected to an ordinary source of A. C. electric energy.

The oxygen which is produced in gaseous form on the face of the cell plates is withdrawn through line 23 and the time element between the generation of the oxygen and its entering the circulating stream of spent caustic is very short, so that the oxygen, which is still very active as contrasted to molecular oxygen, has not had an opportunity to lose its activity or even approach the activity of bottle or molecular oxygen.

The caustic soda which has been used to treat the sour gasoline in packed tower 8 contains mercaptides and other sulfur compounds which have been removed from the gasoline, and when this spent caustic solution is supplied with the oxygen from the electrolytic cell, the mercaptides are converted into disulfides which are insoluble and continue in suspension in the regenerated caustic solution, which flows from the circuit through line 24 into regenerated caustic tank 25.

A pump 26 carries the regenerated caustic containing the disulfides into a disulfide scrubber tank 27 containing naphtha, for example, and the regenerated caustic free from the disulfides flows out from the bottom of the scrubber and returns through line 12 to the top of the treating tower 8.

Other fluids which require oxygen for revivification may also be successfully treated with oxygen, outside of the electrolytic cell where it is generated by means of our invention; another example of such fluid being the spent acid catalyst from a sulfuric acid alkylation process. Such spent acid catalyst has the formula $C_4H_9HSO_4$, and when oxygen as generated in an electrolytic cell is added to this fluid, it results in the production of CO_2 which escapes as a gas and H_2O and H_2SO_4 . The acid and water mixture is brought up to 98% concentration by adding oleum— $H_2SO_4 \cdot SO_3$ in the usual manner.

Another embodiment of our invention is illustrated in Fig. 2, to which reference is now made. Here oxygen as generated in an electrolytic cell is utilized to purify waste waters from oil refineries, paper mills, or the like. The treating of West Texas distillates results in a waste chemical solution composed of sodium polysulfides having a formula Na_2S_4 . This is produced by adding sulfur to sodium sulfide as represented by the formula

Sodium polysulfide waste is very deficient in oxygen and is very detrimental to any lake or river water and cannot safely be discharged without treatment. Such treat-

ment may, however, be accomplished economically by the use of our invention.

The waste process water enters the system through line 35 and is forced by a pump 36 into a tank 37, from thence it is recirculated through line 38 through eductor 39, pressure tank 40 and is returned to the tank 37. The recirculated effluent flowing through the eductor pulls oxygen gas as generated in electrolytic cell 41 and flows through line 42, to the suction side of the eductor. The arrangement is such as to produce thorough mixing of the oxygen with the waste process water.

The cell may have any suitable electrolyte, such as caustic potash and is supplied with direct current by rectifier 43, which in turn is connected to an ordinary source of electric power as indicated at 44.

The oxygen in this case also is utilized in gaseous form before it has lost its initial activity as compared with bottle or molecular oxygen. Thus the time element involved in the depreciation in activity of the oxygen as generated in the electrolytic cell is taken advantage of, so that the oxygen efficiently creates the desired chemical change in the waste water. The formula which we believe represents the change in the particular waste solution above discussed is $4Na_2S_4 + 24O = 4Na_2S_4O_6$, which is sodium tetrathionate, a harmless solution that may be safely discharged into lakes or rivers.

In attempting to employ bottle or molecular oxygen for the herein described oxidizing processes it has been demonstrated that the results are very meager, unsatisfactory and uneconomical in the absence of a catalyst, whereas the oxygen generated in the cell when used quickly gives highly satisfactory and effective oxidation and makes the processes commercially feasible.

According to a specific example of the use of our process, 1800 milliliters of spent treating solution having a mercaptan number of 531 milligrams per 100 milliliters has been regenerated by contacting oxygen as generated in an electrolytic cell in the external system to a treating solution having a mercaptan number of 456 in five minutes by applying a current density of 15 amperes per $\frac{1}{4}$ square foot, which is equivalent to 60 amperes per square foot anode area in the cell.

The efficiency of the process is the weight of mercaptan sulfur oxidized, times 100 divided by the theoretical weight of mercaptan sulfur based on 1.2 grams (see Perry's Chemical Engineering Handbook, 3rd edition, 1950, page 1779) per ampere hour per square foot. Hence the percent oxidation of mercaptan sulfur to disulfide sulfur in the above example is equal to

$$\frac{0.531 - 0.456 \times 18 \times 100}{5 \text{ hr.} \times \frac{60}{4} \times 1.2} = \frac{135}{150} = 90.0$$

An example which is typical of the commercial operation of the process of this invention is as follows:

Caustic treating and regeneration unit

60	Pressure Distillate		Caustic (grams per liter)				Current supplied to cell, amperes	
	Mercaptan Sulfur, percent by weight		Spent		Regenerated			
	In	Out	H_2S	RSH	H_2S	RSH		
50	.02	.0034	0	.80	0	.16	9,000	

Tests made to determine the activity of the oxygen produced electrolytically in direct comparison with bottle or molecular oxygen show that:

(1) Rate of loss in activity of electrolytically produced oxygen is inversely proportionate to the age of the oxygen, i. e., the loss in mercaptan oxidizing ability is fairly rapid during the first one or two minutes after the oxygen is generated in the cell. As the oxygen grows older, it loses its activity at a slower rate.

(2) In the operation of our invention the oxygen

from the cell reaches the caustic solution to be regenerated at the ejector in approximately 58 seconds, and with good mixing in both cases the percentage conversion with the oxygen from the electrolytic cell gives approximately twice the efficiency as bottle oxygen under the same conditions.

(3) Tests indicate that oxygen which is approximately 130 seconds old has lost approximately 20% of its effectiveness during the second minute of its life. The conversion efficiencies of electrolytic oxygen in regenerating spent caustic solution range from 99.5%, with intimate mixing, to 26.4% with poor mixing. Bottle oxygen under the same mixing conditions and applied to the same caustic solution, was approximately one-half as effective as the electrolytic oxygen.

The efficiency of the process if carried on inside of the cell is much lower.

Sufficient water will be added to the cell to make up not only for that which is decomposed but also for any net loss of moisture which escapes with the oxygen and hydrogen gases.

Commercial cells designed to operate at low pressure for the production of oxygen and hydrogen are entirely suitable for use in carrying out our invention, whereas the efficiency of the treating operation is sacrificed and the cell must be made to withstand relatively high pressure conditions at greatly increased cost if the spent treating fluid flows through the cell and is oxidized therein in accordance with the prior art process. In fact, the maximum pressure obtained in a commercial electrolytic cell is too low for the best results.

In referring to oxygen as generated in an electrolytic cell, we mean the oxygen gas produced on the anode of an electrolytic cell, and we have discovered that the time element within which this oxygen fades in activity to that of bottle or molecular oxygen is not instantaneous, as heretofore supposed, but is much longer and, while we now believe that it begins to age or to combine within about 2 minutes, its activity is substantially that of the newly generated oxygen for a sufficient time to obtain caustic regeneration of high efficiency outside the cell where the oxygen is produced.

While we have described the invention as applied to different specific examples, these are intended to be illustrative only, and only such limitations should be imposed as appear in the appended claims.

This application is a continuation-in-part of our application Serial No. 390,055, filed November 3, 1953, now abandoned.

What we claim is:

1. The process of treating sour hydrocarbon oils which consists of pretreating the oil with a caustic wash to remove the hydrogen sulfide (H_2S), washing the oil by a continuous countercurrent stream of caustic solution to remove the mercaptides, electrolytically generating oxygen, regenerating the spent caustic solution containing mercaptides by injecting into the stream of spent caustic solution the oxygen as generated within a time element of 10 minutes and without passing the caustic solution through the electrolytic cell.

2. The process of treating sour hydrocarbon oils which

consists of washing the oil by a continuous countercurrent stream of caustic solution to remove the mercaptides, electrolytically generating oxygen, regenerating the spent caustic solution containing mercaptides by injecting into the stream of spent caustic solution the oxygen as generated within a time element of 2 minutes without passing the caustic solution through the electrolytic cell where the oxygen is produced.

3. The process for treating sour gasoline which consists of removing the hydrogen sulfide (H_2S) without removing the mercaptides, washing the gasoline with a caustic solution to remove the mercaptides, electrolytically generating oxygen independently of said caustic solution and regenerating the spent caustic solution by immediately mixing the oxygen outside of the electric cell where the oxygen is produced within the time element during which the oxygen retains a substantial part of its initial activity as contrasted to molecular oxygen with the spent caustic solution to oxidize the mercaptides to form disulfides.

4. The process for treating sour gasoline which consists of removing the hydrogen sulfide (H_2S) without removing the mercaptides, washing the gasoline with a caustic solution to remove the mercaptides and electrolytically generating oxygen, regenerating the spent caustic solution by immediately mixing the oxygen outside of the electric cell where the oxygen is produced before the activity of the oxygen has had time to depreciate to that of molecular oxygen with the spent caustic solution to oxidize the mercaptides to form disulfides in the absence of a catalyst.

5. The process of regenerating spent caustic solution containing mercaptides which consists of electrolytically decomposing water in an electrolyte solution independent of the caustic solution to form active oxygen, withdrawing the active oxygen from the electrolytic cell and immediately introducing it outside of the cell into and intimately mixing it with the spent caustic solution while the activity of the oxygen is greater than that of molecular oxygen, to form disulfides.

6. The process of regenerating spent caustic solution containing mercaptides which consists of electrolytically decomposing water in an electrolyte solution to form active oxygen, withdrawing the active oxygen from the electrolytic cell and immediately introducing it into the spent caustic solution before the active oxygen has lost its activity as compared to molecular oxygen.

7. The process of claim 6 in which the electrolyte is chemically dissimilar from the spent caustic solution.

50 8. The process of claim 6 in which the caustic solution containing mercaptides is a caustic soda solution and the electrolyte is a caustic potash solution.
